Primary Examiner — Michael C Stout*Assistant Examiner* — Thanh Luu Wong(74) *Attorney, Agent, or Firm* — Jeff B. Vockrodt; CM Law(57) **CLAIM**

The ornamental design for a dermal spray cartridge, as shown and described.

DESCRIPTION

FIG. 1 is a perspective view of top, front, and left sides of a dermal spray cartridge showing our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict portions of the dermal spray cartridge that form no part of the claim.
